UNITED STATES PATENT OFFICE.

GARRY I. MIX, OF YALESVILLE, CONNECTICUT.

DESIGN FOR A SPOON.

SPECIFICATION forming part of Design No. 18,290, dated May 1, 1888.

Application filed November 30, 1887. Serial No. 256,571. Term of patent 14 years.

To all whom it may concern:

Be it known that I, GARRY I. MIX, of Yalesville, in the county of New Haven, and in the State of Connecticut, have invented a certain 5 new and useful Design for Spoons; and I do hereby declare that the following is a full, clear, and exact description thereof, reference being had to the accompanying drawings, in which—

Figure 1 is a front elevation of a spoon having my design, and Fig. 2 is a rear elevation of the same.

Letters of like name and kind refer to like parts in each of the figures.

The principal feature of my design consists 15 in a band, a , which extends in a curve across the upper end of the handle of the spoon A, is defined by raised beads a' and a'' at its upper and lower edges, and has at suitable points upon its face star-shaped figures a^1 and a^2 . The 20 face of said band is ornamented by a series of equidistant parallel lines.

Another feature of my design consists in a band, a^3 , which extends in a curve across the central portion of the handle of the spoon, with 25 its upper and lower edges defined by elongated bead-like projections a^4 and a^5 , and upon its face has a number of semi-spherical protuberances, a^6 and a^7 , that are centrally arranged in a line corresponding to the curvature of said band. The face of said band is also ornamented by a series of equidistant parallel lines.

Another feature of my design consists in a raised line, a^8 , which extends along each edge of the upper portion of the spoon-handle and connects the bands a and a^3 .

Another feature of my design consists in a band, a^9 , which extends in a straight line across the spoon-handle near its upper end, with its face ornamented by a series of equidistant parallel lines and its edges defined by two raised beads, a^9 and a^{10} , and upon its face a number of star-shaped figures, a^9 and a^{10} .

Another feature of my design consists in a band, a^{11} , which extends in a curve across the 45 handle of the spoon, with its upper edge defined by a raised bead, a^{11} , and its lower edge by the

row of bead-like projections a^4 and a^5 . Said band is ornamented by a number of leaves, a^{12} and a^{13} , which extend from its lower edge upward, and a flower and stem, a^{14} , that extends 50 upward from between the contiguous edges of said leaves. The face of said band is cross-hatched, as shown.

Another feature of my design consists of a panel, a^{15} , which extends between the bands a^1 and a^{10} , and is divided by a band, a^{16} , that extends diagonally across the same from its upper end to its lower end. Said band a^{16} is ornamented by a series of transversely-arranged parallel lines, and has extending lengthwise of 60 the same a vine, a^{17} . In one of the lower corners of said panel is a fan-shaped figure, a^{18} , while across its upper end is a row of bead-shaped protuberances, a^{19} .

Another feature of my design consists in a 65 panel, a^{19} , which extends between the bands a^1 and a^7 , and has its surface ornamented by vertically-arranged half-round ribs a^{20} and a^{21} .

Another and the last feature of my invention consists in the entire design, as herein 70 shown and described.

Having thus described my invention, what I claim is—

1. The design for a spoon handle herein shown and described, the same consisting of 75 the panel a^{14} , which is divided by the diagonal band a^{16} , having the vine a^{17} , and has the fan-shaped figure a^{18} placed in its lower corner and the row of beads a^{19} across its upper end, substantially as set forth.

2. The design for a spoon-handle herein shown and described, the same consisting of the entire ornamentation, substantially as set forth.

In testimony that I claim the foregoing I have hereunto set my hand this 27th day of September, 1887.

GARRY I. MIX.
